SEPARATELY FIRED PREHEATER FOR GAS-EOUS FLUIDS WITH RECIRCULATION OF GASES OF COMBUSTION

Per Hilmer Karlsson, Wellsville, and Ernest A. Lundstrom, Valley Stream, N. Y., assignors to The Air Preheater Corporation, New York, N. Y.

Application August 8, 1945, Serial No. 609,578

5 Claims. (Cl. 126—110)

1

The present invention relates to heat exchangers and particularly to apparatus for transmitting heat from one gaseous fluid to another wherein a separately fired furnace is utilized to provide the heating medium rather than a boiler or source of waste heat.

Some industrial processes require that a gaseous medium be heated under circumstances where fuel has to be burned especially for this purpose because the heating gases cannot be derived from a boiler or source of waste heat. However, the employment of a separately fired heat exchanger for this purpose presents the disadvantage that the temperature of gases when burning fuel with normal excess air is too high to be handled by a heat exchanger of conventional type having metallic surfaces for transmitting heat from the heating medium to the gas that is to be heated. In order to lower the temperature of the gases to a point suitable to be passed through the preheater it has been proposed to dilute the gases with cold air or alternatively to recirculate part of the flue gases through the furnace. The recirculation of flue gases ordinarily requires the provision of elaborate and expensive duct work to connect the outlet of the preheater with the furnace for recirculating part of the gases and with a stack for disposing of the remainder.

The present invention contemplates avoidance of the above disadvantages by the provision of a furnace and preheater so constructed and compactly arranged as to minimize the amount of duct work required.

In the drawings:

Figure 1 is an elevational view partly in section of a separately fired preheater embodying the present invention; and

Figure 2 is a plan view of the apparatus illustrated in Figure 1.

Referring to the drawings, the numeral 10 designates a furnace, preferably in the form of a vertically disposed cylinder, having one or more fuel burners 11 in its top end wall for introducing a fuel and air mixture into the furnace in a downward direction. Spaced outwardly from the composite refractory and insulation wall 12 of the furnace is a casing 13 thus providing a space surrounding the furnace which is subdivided by vertically spaced partitions 14, 15 to form upper, intermediate and lower chambers 16, 17 and 18, respectively. Above and below the partition 15 are rows of ports or openings 20, and 21 spaced circumferentially and arranged in rows around the wall 12 and placing the interior of the furnace in communication with the cham-

bers 17 and 18, respectively, both rows of openings being located below the zone of combustion in the furnace.

The gases of combustion from furnace 10 pass through the openings 21 into the chamber 18 and exit from the latter through an outlet opening 22 that is aligned with the gas inlet 23 of a vertically arranged rotary, regenerative preheater 24 of the Ljungstrom type such as shown in Patent No. 1,652,025, dated December 6, 1927.

The body of the air preheater 24 is vertically disposed in a position or at a level opposite the intermediate chamber 17 and does not encroach substantially upon the space opposite the upper and lower chambers 16 and 18 so that with the gas passage of the preheater contiguous to the casing 13 the inlet and outlet ducts 23, 27 leading to the preheater rotor on the gas side may be disposed in alignment with openings formed in the casing 13 and leading to the chambers 18 and 16, respectively.

Having passed over the heat transfer surface carried in the rotor of the preheater the cool gases are discharged from the gas passage of the preheater through the outlet 27 which is aligned with an inlet opening 28 formed in the casing 13 and leading to the upper chamber 16. At the other side of casing 13 (diametrically opposite as shown) an outlet opening 31 places the chamber 16 in communication with a duct 32 leading to the suction side 33 of an induced draft fan 34. A branched outlet duct is provided on the discharge side of the fan 34, one branch 35 leading to a stack 36 while the branch 37 extends to an inlet opening 38 in casing 13 leading to the intermediate chamber 17.

The air or other gaseous fluid to be heated is supplied by a forced draft fan 40 to the inlet 41 on the "air" side of the preheater and discharged through the outlet duct 42 into a conduit 43 that extends to the point of use. The amount of gas recirculated under the control of a damper 39 in the outlet duct for fan 34 is caused to enter the furnace 10 substantially uniformly circumferentially of the furnace by having the openings 45 20 facing the gas return port 38 of a considerably smaller size than those at the opposite side of the furnace so that some of the gas must flow through the chamber 17 and around the furnace to enter the latter at points spaced circumferentially of the chamber as well as near the point of admission thereto. For similar reason the openings 21 leading from the furnace 10 into the lower chamber 18 are smaller on the side facing the casing outlet 22 leading to the heat exchanger

24. Thus, a substantially uniform mixture of recirculated gases and products of combustion is effected in the furnace and this is aided by causing the greater proportion of the gases to leave the furnace on the side remote from the heat exchanger and thereby avoiding an outrushing of the gases through the openings on the right hand side directly facing the casing outlet opening 22.

What we claim is:

1. A separately fired heat exchange unit comprising; a vertically disposed cylindrical furnace having downwardly firing fuel burners in its upper end wall; a casing spaced radially outward of the side wall of said furnace; means closing the spaces between upper and lower ends of said casing and said furnace; vertically spaced partitions dividing the enclosed space around said furnace into upper, lower and intermediate chambers, the wall of said furnace being formed circumferentially thereof with openings arranged in groups spaced axially of the furnace and placing it in communication with the lower and intermediate chambers; an indirect type heat exchanger mounted adjacent one side of said casing with the inlet and outlet of its passage for the heating medium disposed contiguous to said casing; an outlet for said lower chamber and an inlet for the upper chamber both formed in said casing on the side adjacent said heat exchanger; means connecting said outlet with the lower end and said inlet with the upper end of said heat exchanger passage; an outlet for said upper chamber formed in said casing at the side opposite its inlet; an induced draft fan having its inlet connected with the outlet of said upper chamber; an inlet for said intermediate chamber formed in said casing at the side opposite said heat exchanger; a duct connected to the discharge side of said fan having a pair of branches communicating respectively with a gas outlet for the system and with the inlet to said intermediate chamber so arranged in conjunction therewith as to direct part of the products of combustion that flow serially from the furnace through said lower chamber, said heat exchanger passage and said upper compartment, back into said furnace via said intermediate chamber; and means for circulating a fluid to be heated through said heat exchanger.

2. A separately fired heat exchange unit comprising; a vertically disposed cylindrical furnace having downwardly firing fuel burners in its upper end wall; a casing spaced outwardly from the side wall of said furnace and closed at its upper and lower ends; vertically spaced partitions dividing the enclosed space around said furnace into upper, lower and intermediate chambers, the wall of said furnace being formed circumferentially thereof with spaced openings arranged in groups axially of the furnace and placing it in communication with the lower and intermediate chambers; an indirect heat exchanger mounted adjacent one side of said casing with the inlet and outlet of its passage for the heating medium disposed contiguous to said casing; an outlet for said lower chamber and an inlet for the upper chamber formed in said casing on the side adjacent said heat exchanger; means connecting said outlet with the lower end and said inlet with the upper end of said heat exchanger passage; an outlet for said upper chamber formed in said casing in circumferentially spaced relation to its inlet; an induced draft fan having its inlet connected with the outlet of said upper

chamber; an inlet for said intermediate chamber formed in said casing adjacent said fan; a duct connected to the discharge side of said fan having a pair of branches communicating respectively with a gas outlet for the system and with the inlet to said intermediate chamber so arranged in conjunction therewith as to direct part of the products of combustion that flow serially from the furnace through said lower chamber, said heat exchanger passage and said upper chamber, back into said furnace via said intermediate chamber; damper means in said duct for regulating the volume of gas entering said intermediate chamber, and means for circulating a fluid to be heated through said heat exchanger.

3. A separately fired heat exchange unit comprising; a furnace having fuel burners in an end wall thereof; a casing surrounding said furnace and spaced outwardly from its side wall to enclose a space around said furnace, the wall of said furnace being formed circumferentially thereof with spaced openings arranged in axially spaced rows and placing said furnace in communication with said enclosed space; a partition located between said rows to form two contiguous chambers; an indirect heat exchanger mounted adjacent one side of said casing with the inlet and outlet of its passage for the heating medium disposed contiguous to said casing; an outlet for the one chamber remote from said fuel burners formed in said casing on the side adjacent said heat exchanger; means connecting said chamber outlet with the inlet end of said heat exchanger passage; an induced draft fan having its inlet connected to the outlet of said passage; an inlet for said other chamber formed in said casing adjacent said fan; a duct connected to the discharge side of said fan having a pair of branches communicating respectively with a gas outlet for the system and with the inlet to said other chamber so arranged in conjunction therewith as to direct part of the products of combustion that flow serially from the furnace through said one chamber, said heat exchanger passage, back into said furnace via said other chamber; damper means in said duct for regulating the volume of gas entering said other chamber; and means for circulating a fluid to be heated through said heat exchanger.

4. A separately fired heat exchange unit comprising; a vertically disposed furnace having downwardly firing fuel burners in its upper end wall; a casing surrounding said furnace and spaced outwardly from the side wall of said furnace to enclose a space around it, the wall of said furnace being formed circumferentially thereof with spaced openings arranged in axially spaced groups and placing said furnace in communication with said enclosed space; a horizontal partition located between said groups of openings and forming two contiguous superimposed chambers; an indirect heat exchanger mounted adjacent at one side of said casing with the inlet and outlet of its passage for the heating medium disposed contiguous to said casing; an outlet for the lower one of said chambers formed in said casing on the side adjacent said heat exchanger; means connecting said chamber outlet with the inlet end of said heat exchanger passage; an induced draft fan having its inlet connected with the outlet of said passage; an inlet for the other of said chambers formed in said casing adjacent said fan; a duct connected to the discharge side of said fan having a pair of branches communicating respectively with a gas outlet for the sys-

tem and with the inlet to said other chamber so arranged in conjunction therewith as to direct part of the products of combustion that flow serially from the furnace through said one chamber, said heat exchanger passage, back into said furnace via said other chamber; and means for circulating a fluid to be heated through said heat exchanger.

5. A separately fired heat exchanger as recited in claim 3 wherein the openings in the wall of said furnace that place it in communication with said two contiguous chambers vary in size circumferentially of said wall with the smallest openings opposite the inlet of one chamber and the outlet of the other chamber and the largest openings formed in portions of the wall at the side diametrically opposite said inlet and outlet respectively.
